[57] CLAIM

The ornamental design for a vineyard crossarm with antisway notches, as shown and described.

DESCRIPTION

FIG. 1 is a top plan view of a first embodiment of a vineyard crossarm with antisway notches, as shown in FIG. 1;

FIG. 2 is a front elevational view of a vineyard crossarm with antisway notches, showing my new design;

FIG. 3 is a bottom plan view of FIG. 2;

FIG. 4 is a rear elevational view of FIG. 2;

FIG. 5 is a left end view of FIG. 2;

FIG. 6 is a right end view of FIG. 2;

FIG. 7 is a perspective view of the design of FIG. 2, looking toward the rear; and,

FIG. 8 is a perspective view of a second embodiment of the vineyard crossarm with antisway notches, looking toward the rear and left end, with the other end being a mirror image thereof.
